(57) **CLAIM**

The ornamental design for a frame and curb box, as shown and described.

DESCRIPTION

FIG. 1 is a top, front and right side perspective view of the frame and curb box of the present invention.

FIG. 2 is a bottom, front and right side perspective view of the frame and curb box of FIG. 1.

FIG. 3 is a top view of the frame and curb box of FIG. 1.

FIG. 4 is a front elevational view of the frame and curb box of FIG. 1.

FIG. 5 is a right side elevational view of the frame and curb box of FIG. 1.

FIG. 6 is a rear elevational view of the frame and curb box of FIG. 1; and,

FIG. 7 is a bottom view of the frame and curb box of FIG. 1. The left side elevational view of the frame and curb box is a mirror image of the right side elevational view.

FIGS. 1 and 3-6 show portions of the frame and curb box in phantom lines. The phantom lines show boundaries of the design and elements of the frame and curb box that form no part of the claimed design.
